(Cl. D44—21)

FIGURE 1 is a perspective view of a milk carton holder, showing my new design;

FIGURE 2 is a top plan view;

FIGURE 3 is a side elevational view;

FIGURE 4 is a side elevational view taken from the side opposite that in FIGURE 3; and

FIGURE 5 is a bottom plan view.

The characteristic feature of the design resides in the combination on a holder of the configuration shown of diamond shape cut-outs at the corners occupying a major portion of the height thereof and a handle of substantially uniform width flaring to a greater width at its upper point of attachment, all as shown.

I claim:
